UNITED STATES PATENT OFFICE

2,388,914

POT TYPE BURNER WITH SCOOP PILOT RING

Bruce Hayter, Santa Fe, N. Mex., assignor to Oil Devices, Santa Fe, N. Mex., a limited partnership of Illinois

Application March 14, 1942, Serial No. 434,665

1 Claim. (CL 158—91)

My invention relates to an improvement in pot type oil burners and particularly to an improvement in pilot rings or baffles employed intermediate top and bottom of such burners.

One purpose is to provide improved means for controlling the admission of primary air at the pilot stage.

Another purpose is to provide an improved form of baffle ring.

Another purpose is to provide improved means for controlling the ratio between the primary and secondary air.

Other purposes will appear from time to time in the course of the specification.

I illustrate my invention more or less diagrammatically in the accompanying drawing wherein:

Fig. 1 is a vertical axial section; and

Fig. 2 is a section on the line 2—2 of Fig. 1.

Like parts are indicated by like symbols throughout the specification and drawing.

Referring to the drawing, 1 generally indicates any suitable outer housing, which may be of any suitable shape and proportions but which I illustrate as a generally cylindrical drum. It may be supported on any suitable means, for example the feet 2. 3 is a bottom partition having a central air inlet aperture 4. 5 indicates a burner pot, having a bottom portion 6, and an outwardly extending top flange 7, which may rest upon any suitable supporting ring 8, inwardly extending from an inner wall of the outer housing 1. 9 is a flame ring centrally apertured as at 10. 11 indicates a plurality of primary air inlet apertures, which are herein shown as located at a single level or in a single row. 12 indicates a plurality of secondary air inlet apertures, located at a higher level and upwardly and inwardly tilted, and more closely spaced and larger in cross sectional area than the primary inlet apertures 11. It will be understood, of course, that the air inlet apertures may be otherwise arranged and that other means may be employed for supplying secondary air to the upper portion of the pot. However, the structure herein shown is a practical and operative structure.

14 indicates any suitable liquid fuel pipe which extends to a source of liquid fuel not herein shown. It will be understood that any suitable means not herein shown may be employed for varying or controlling, automatically or manually, the flow of liquid fuel along the pipe 14. It will be understood that preferably a minimum flow is provided so that the fire in the pot is constantly maintained and never drops below the so-called pilot stage.

15 indicates a baffle ring or pilot ring centrally apertured as at 16, and supported on any suitable supports, such as the pins 18 inwardly extending from the wall of the pot 3. The ring is shown as slightly frusto-conic and is provided about its periphery with a plurality of scoops 17 which extend downwardly below the level of the primary air inlet apertures 11 and blank out a certain number of them. It will be understood that such of the apertures 11 as are out of line with the scoops deliver the primary air to the space below the baffle 15, whereas such as are aligned with the scoops deliver air to the space above the baffle 15. A conical pin 19 secured in the wall 5 engages a notch 18a in the baffle ring 15 and assures the alignment of the holes 11a with the scoops 17.

At the pilot stage the fuel flowing in through the pipe 14 to the bottom 8 is vaporized by the heat of combustion taking place at the general level of the pilot ring 15. The apertures 11 which deliver below the pilot ring provide primary air for the mixture, and the mixture of primary air and vaporized fuel receives the secondary air at or above the plane of the aperture 16 of the pilot ring 15. At this stage at least part of the secondary air supply is provided by the air inlets 11 which are blanked out by the scoops 17. The size of the holes may be differential, and it will be observed, as in Fig. 2, that the holes 11 are of smaller cross sectional area than the individual holes 11a which are blanked out by the scoops. In other words, by the employment of the differential size of the apertures, or by the employment of pilot rings having scoops of various arcs of extension, or both, I can take off as much of the air coming in at the primary level as I want to and deliver it as secondary air to the space above the baffle 15. Thus, the ratio of the primary and secondary air may be controlled as desired.

It will be understood that, whereas at the pilot stage the air delivered below the pilot ring serves as primary air, and the air delivered above the pilot ring serves as secondary air, at the high fire stage, all of the lower apertures serve as primary air inlets, and the secondary air is delivered to the mixture through the secondary air inlet apertures 12.

It will be realized that, whereas I have illustrated and described a practical and operative device, nevertheless many changes may be made in the size, shape, number and disposition of parts without departing from the spirit of my invention. I therefore wish that the description and drawing be taken as in a large sense illustrative

and diagrammatic, rather than as a limitation to the precise showing.

I claim:

In a pot type burner, a burner pot having a circumferential side wall and a bottom, means for delivering liquid fuel to a lower portion of the pot for vaporization, said side wall having primary air inlet apertures extending about the pot intermediate the top and bottom of the pot, means for delivering secondary air to an upper portion of the pot, a baffle ring located adjacent the level of said primary air inlet apertures, some

5
10

of the primary air inlet apertures being positioned to deliver air below the baffle ring, the baffle ring having downwardly extending scoop portions aligned with other of said primary air inlet apertures and adapted to direct primary air to the interior of the pot above said baffle ring, the air inlet apertures aligned with said scoop portions being of materially larger diameter than the other primary air inlet apertures and in communication with the space below the baffle ring.

BRUCE HAYTER.
